UNITED STATES PATENT OFFICE.

LEO POTTER, OF NEW YORK, N. Y., ASSIGNOR TO LEO POTTER INC., OF NEW YORK, N. Y., A CORPORATION OF NEW YORK.

IRONING MACHINE.

Application filed June 11, 1921. Serial No. 476,667.

This invention relates to ironing machines and particularly to machines of the type having a pressing or feeding roller and a heated ironing element or shoe.

5 One of the objects of the invention is to provide means for automatically moving the ironing elements of an ironing machine to operative position upon the starting of the driving means for the machine.

10 Another object of the invention is to provide means for automatically releasing the operative ironing elements from ironing or feeding position upon the cutting off of the driving means for the machine.

15 Another object of the invention is to provide an ironing machine having a rotating element supported in such a manner as to leave the ends of the element unobstructed.

Another object of the invention is to provide 20 an ironing machine having means for feeding the material to be ironed into the machine at the front and for feeding the ironed material out of the machine at the front.

25 Another object of the invention is to provide an ironing machine with means for supporting and guiding overlapping ends of the material being ironed.

Another object of the invention is to provide 30 means in an ironing machine for automatically and immediately moving the feeding element away from the ironing element upon the stopping of the feed of the material between the elements.

35 Another object of the invention is to provide a machine of the character described mounted in such a manner as to be folded into a cabinet.

Further objects of the invention will appear 40 from the following specification taken in connection with the drawings which form a part of this application and in which

45 Fig. 1 is a top plan view of an ironing machine constructed in accordance with my invention.

Fig. 2 is a front elevational view partly in section of the machine shown in Fig. 1, the motor being omitted.

50 Fig. 3 is an end elevation partly broken away and partly in section showing the driving connections for the feeding element or roller.

Fig. 4 is a front elevation partly in sec-

tion showing the driving connections between the motor and the intermediate power 55 transmitting shaft.

Fig. 5 is a detail elevational view showing a motor control switch and operative means for the switch.

Fig. 6 is an end elevation of the construction shown in Fig. 5.

Fig. 7 is a detail sectional view on an enlarged scale showing the driving connections between the motor shaft and the roller shaft.

Fig. 8 is an elevational view on an enlarged scale showing the rack and pinion connection for moving the roller into engagement with the ironing element.

Fig. 9 shows in perspective one of the end brackets for supporting the roller shaft, 70 this bracket also having formed thereon the rack for moving the roller toward the ironing element, and

Fig. 10 illustrates in elevation a mounting of my ironing machine upon a folding 75 platform whereby it may be folded into a cabinet.

Briefly stated the objects of the invention above outlined are attained in the embodiment of the invention illustrated by providing operative driving connections between the motor and the feeding element and further by providing yieldable means connected to the feeding element or roller for moving the roller bodily toward the ironing element or shoe upon the rotation of the roller. Means is also provided for automatically and immediately separating the ironing elements upon the stopping of the feed of material therebetween. The ironing elements 80 are also so mounted as to leave them free at their ends whereby material may overlap thereby enabling the operator to iron material wider than the length of the ironing elements by ironing successive widths of the 85 material.

Referring to the drawings, wherein like characters of reference designate corresponding parts, I have shown an ironing machine comprising frame members 20 connected by longitudinal brace rods 21, the members 20 being angular in shape. An ironing element or shoe 22 is supported in any suitable manner by the vertical portions 23 of the members 20. The ironing element 22 may be 100 heated in any desired manner, as by elec-

tricity, gas or steam and these different elements may be used interchangeably, if desired.

The feeding element or roller 24 is supported at its ends by brackets 25 and 26, these brackets being recessed as shown at 27 to receive the overlapping material. The brackets are secured in any suitable manner as by screws 28 to the frame members 20.

- 10 As shown in Figs. 1 and 9 the free ends of the brackets are offset laterally from the remaining portions of the brackets and support the ends 29 and 30 of the roller shaft in slots 31' whereby the shaft may move laterally in a manner hereinafter described. From the showing, particularly in Fig. 2, it will be noted that the ends of the brackets supporting the roller shaft are disposed within the periphery of the roller and do not overlap this periphery and because of this the material being fed through the machine may overlap the ends of the roller and shoe. This is particularly advantageous since it permits the operator to iron successive widths of a piece, the total width of which is much greater than the length of the ironing elements or the width of the machine.

In order to support the overlapping ends of the material, I have provided troughs or pans 31 and 32, these troughs being preferably formed integral with a supporting and guiding member 33 which extends from the bottom of the ironing element or shoe substantially to the front of the machine. By means, therefore, of the troughs 31 and 32 of the supporting member 33, the material being ironed will be guided and fed back to the front of the machine where it may be easily and readily handled by the operator.

- 40 A table or supporting member 34 is secured in any suitable manner to the frame members 20, this table being partly supported by the portions 35 of the brackets 25 and 26. As shown in Fig. 3 the table extends over a part of the top of the feeding roller 24 and guides the material to the roller.

The driving mechanism for the feeding roller will now be described. A motor 36 is supported in any suitable manner from the table 34 and if desired by suitable braces carried by the frame members 20. The motor 36 is preferably electrical and lead wires 37 and 38 may be connected to any suitable source of power and a controlling switch 39' is secured to the under side of the table 34 for controlling the motor.

- 50 As shown in Fig. 4 the motor shaft 39 is connected through a worm 40 and worm gear 41 to a shaft 42. The latter shaft is splined as shown at 43 to a shaft 44 and this shaft is connected through a worm 45 and worm gear 46 to one end of the feed roller shaft 29. Gears 45 and 46 are enclosed in a casing 47. As shown in Figs. 3 and 7 the shafts

42 and 44 telescope and a casing 47' extends over the telescoping portions of the shafts. The driving connections just described are also preferably enclosed, the gearing at the motor end being enclosed by casings 48 and 49 and the gearing at the roller end being enclosed by a casing 47.

From the above description, it will be noted that when the motor is started the roller will be rotated.

I will next describe the means for automatically moving the feeding element or roller into operative relation with the ironing element upon the rotation of the roller. Each end of the roller is recessed as shown at 50 and a pinion 51 rotatably mounted on the shaft 29 is provided with a flanged portion 52 positioned in the recessed portion 50 of the roller. A ring or disc of suitable frictional material 53 is positioned between the flange 52 and the recessed portion 50 and a spring 54 resiliently presses the pinion and flange against the portion 50 thereby communicating the rotational movement of the roller to the pinion.

As shown in Figs. 1, 2 and 8 the brackets 25 and 26 are provided with offset portions 55, each of which has formed on its upper surface a rack 56 and the pinions 51 mesh with the racks 56.

As shown in Fig. 2, the bracket 25 at the left hand end of the roll has a wider space outside the offset portion 55 to provide sufficient space to receive the gears 45 and 46.

The movement of the feeding roller into operative position will now be described. As the motor is started and the roller is driven in the manner already defined, the pinions 51 will be rotated, being driven frictionally by the roller. As these pinions are rotated they will travel on the racks 56 in a direction toward the ironing element or shoe 22, it being remembered that the ends of the roller shaft 29 are mounted in slots 31'. This frictional driving connection between the roller and the pinions 51 will cause a constant pressure of the roller against the ironing element whereby the material will be fed between these elements and ironed.

In machines of this character unless means is provided for immediately separating the feeding and the ironing elements when the motor stops or when the feed roller ceases to rotate, the material being ironed will be burned or scorched. The means for accomplishing this separation of the elements in the embodiment of the invention illustrated is shown particularly in Fig. 8 and comprises a pair of spring pressed plungers 57 mounted respectively at the two ends of the roller shaft and adapted to force the shaft away from the ironing element upon the stopping of the rotation of the feed roller.

When the feed roller stops rotating the frictional drive of the pinions 51 will cease and therefore the pinions may be rolled back on the racks 56 thereby moving the roller away from the ironing element.

In Figs. 3, 5 and 6 of the drawings, I have illustrated a safety device for stopping the motor and thereby stopping the feeding of the material. This safety device comprises a rod or bar 60 carried by arms 61 secured to the ends of a shaft 62 mounted in the vertical portions 23 of the frame members 20. A stop 63 is carried by each portion 23 for limiting the movement of the arms 61 in a direction away from the roller. The shaft 62 carries an arm 64 slotted at its free end as shown at 65. A pin or button 66 is carried by a snap switch 67 and extends through the slot 65 in the arm 64. The switch 67 is so constructed that the movement of the button 66 by the arm 64 will make and break the circuit. As shown in the full line position in Fig. 6 the circuit is closed and when the rod and arms are moved to the dotted line position the circuit will be opened and the motor will be stopped. It will be noted that the rod 60 extends throughout the length of the roller 24 and is positioned between the edge of the table 34 and the ironing element 22. This rod is also disposed close enough to the surface of the feed roller so that should the fingers or hands of the operator move with the roller they will engage the rod and shut off the bar before they reach the ironing element and are pressed between the feeding roller and this element. The motor may be started and stopped therefore, by throwing the rod 60 forward or backward, as well as by the control switch 39.

In Fig. 2 a snap switch 68 is shown for controlling the heating element and a thermometer or heat indicator 69 is suitably connected to the heating element and indicates the temperature thereof.

In Fig. 10 the ironing machine above illustrated and described is shown as carried by support 70 hinged as shown at 71 to a cabinet 72. A spring 73 engages the hinge 71 and the support 70 and tends to swing this support outwardly. A locking member 74 shown in the form of a pin is provided for retaining the ironing machine within the cabinet and as this pin is pulled out the machine will swing upwardly to the dotted line position.

From the above description, it will be seen that a machine has been provided having the ironing elements so supported that a greater width of material may be threaded therethrough than the length of the ironing elements and further that means has been provided for automatically moving the feeding element into operative position upon the rotation thereof and that the provision has

been made for automatically moving the feeding element away from the ironing element upon the stopping of the feed. The machine also embodies means for supporting and guiding the overlapping material 70 whereby this material is returned to the front of the machine where it can be easily handled by the operator.

Although a specific embodiment of the invention has been described and illustrated, 75 it will be understood that the invention is capable of modification and that changes in the construction and in the arrangement of the cooperating parts may be made without departing from the spirit or scope of the invention as expressed in the following claims.

What I claim is:

1. In an ironing machine, a roller, a shoe, motive power, and means connected to said motive power and to the roller in all positions thereof for rotating and rolling said roller bodily on its axis toward the shoe upon the application of power thereto.

2. In an ironing machine, a roller, a shoe, means for rotating said roller and means including a member operatively connected to and operative by said roller for moving the roller toward said shoe.

3. In an ironing machine, a roller, a shoe, means for rotating said roller and means including a friction clutch operatively connected to and operative by said roller for moving said roller toward said shoe.

4. In an ironing machine, a roller, a shoe, means for rotating said roller and means including a pinion driven by said roller, and a rack engaged by said pinion for moving said roller toward said shoe when the roller is rotated.

5. In an ironing machine, a roller, a shoe, 105 means for rotating said roller, and means including a member having a slip driving connection driven by said roller for moving said roller toward the shoe and retaining the roller in engagement therewith when the roller is rotated.

6. In an ironing machine, a roller, a shoe, means connected to said roller for rotating the roller, a pinion driven by said means through a slip driving connection, and a 115 stationary rack engaged by said pinion and adapted to cause said pinion to move the roller toward the shoe upon the rotation of the pinion.

7. In an ironing machine, a shaft, a roller carried thereby, driving means connected to said shaft, a shoe, a pinion, a friction driving connection between said shaft and said pinion, and a stationary rack meshing with said pinion.

8. In an ironing machine, a roller, a shoe, means for supporting the roller in a manner whereby the ends of the roller will be unobstructed thereby permitting the material to extend freely through the ends thereof, and 130

- means for supporting and guiding material extending beyond the ends of the roller as said material passes around the roller.
9. In an ironing machine, a roller, a shoe, means for supporting the roller in a manner whereby the ends of the roller at the active portion thereof will be unobstructed thereby permitting the material to extend freely through and beyond the ends thereof, and means for supporting and guiding to the front of the machine material extending beyond the ends of the roller.
10. In an ironing machine, a roller, a shoe, means for supporting the roller in a manner whereby the ends of the ironing and feeding portion of the roller will be unobstructed thereby permitting the material to extend freely through the ends thereof, and grooved members for supporting and guiding to the front of the machine material extending beyond the ends of the roller.
11. In an ironing machine, a roller, a shoe, means for supporting the roller in a manner whereby the ends of the active portion of the roller will be unobstructed thereby permitting the material to extend freely through the ends thereof, and troughs disposed at the ends of the roller for supporting and guiding to the front of the machine material extending beyond the ends of the roller.
12. An ironing machine comprising a roller, a shoe, means for supporting and guiding material from the front of the machine to the roller, and means extending substantially to the delivery edge of the shoe for receiving, supporting and guiding material from the roller and shoe to the front of the machine.
13. An ironing machine comprising a roller, a shoe, means for supporting and guiding material from the front of the machine to the roller, and means extending beyond the ends of the roller and substantially to the delivery edge of the shoe for supporting and guiding material from the roller and shoe to the front of the machine.
14. In an ironing machine, a roller, a shoe, means for rotating said roller, operative connections whereby the rotation of said roller will cause the roller to move toward said shoe, and means for moving said roller away from said shoe when said roller ceases to rotate.
15. In an ironing machine, a roller, a shoe, means for rotating said roller, operative connections whereby the rotation of said roller will cause the roller to move toward said shoe, and automatically operable means for moving said roller away from said shoe when said roller ceases to rotate.
16. In an ironing machine, a roller, a shoe, motive power for rotating the roller, means connected to said motive power for automatically moving the roller into operative relation with the shoe when the motive power is started, and means for moving said roller away from said shoe when the motive power is stopped.
17. In an ironing machine, a roller, a shoe, means for rotating said roller, operative connection whereby the rotation of said roller will cause the roller to move toward said shoe, and resiliently actuated means for moving said roller away from said shoe when said roller ceases to rotate.
18. In an ironing machine, a roller, a shoe, a motor, a shaft driven by said motor, a second shaft telescoping with said first shaft and operatively connected to said roller and means operative by the rotation of the roller for moving said roller toward said shoe.
19. In an ironing machine, a roller, a shoe, a motor, a shaft driven by said motor, a second shaft telescoping with said first shaft and operatively connected to said roller, said operative connection between the second shaft and roller including a slip connection and means coacting with and operative by the connection between the second shaft and the roller for moving the roller toward the shoe.
20. In an ironing machine, a roller, a shoe, means operative by the rotation of the roller for moving the roller toward said shoe, a motor, a shaft driven by said motor, a second shaft telescoping with said motor driven shaft and worm gearing between said first shaft and said motor and worm gearing between said second shaft and said roller.
21. In an ironing machine, a roller, a roller shaft, a supporting bracket therefor permitting transverse and rotational movement of said shaft, a pinion, slip driving connections between the pinion and said shaft, a rack carried by said bracket and engaging said pinion, and means for driving said shaft.
22. In an ironing machine, a roller, a shoe, motive power for rotating the roller, means connected to said motive power for automatically moving the roller into operative relation with the shoe when the motive power is started, and means for automatically moving said roller away from said shoe when the motive power is stopped.
23. In an ironing machine, a roller, a shoe, means including brackets for supporting the roller at points inside the periphery thereof, said brackets crossing the ends of the roller only at the non-feeding and non-ironing portions thereof and spaced materially beyond the ends of the roller whereby the periphery at the ends of said non-feeding and non-ironing portions of the roller will be free from obstruction.
24. In an ironing machine, a roller, a shoe, means for supporting the roller in a manner whereby the portion of the roller sur-

face coacting with the shoe to iron the material will be free and unobstructed at and beyond the ends thereof and means for supporting and guiding the material overlapping the ends of the roller.

25. In an ironing machine, a roller, a shoe, means for suspending the roller in a manner whereby the ends of the working portions of the roller are free from obstruction and driving connections for the roller, the driving connections being so located with reference to the circumference of the roller as not to interfere with the passage of the overlapping ends of the material that is being ironed and means for supporting and guiding the overlapping ends of the material as the material passes around the roller and for guiding the material to the front of the machine.

20 26. In an ironing machine, a roller, a shoe, means for supporting the roller in a manner whereby the ends of the roller, and the ends of the shoe are entirely free from obstruction at their entire ironing surfaces, permitting the free passage of the material that is being ironed and its overlapping ends, and means for guiding the material from the front of the machine to the front of the machine without obstruction at 30 the ironing portions of the ends of either the roller or the shoe.

27. In an ironing machine, a roller, a shoe, said roller coacting with said shoe for a portion of its circumference to iron and feed the material, and means for supporting said roller at that section of the roller which is not used for ironing and feeding, thereby permitting the free passage, at the ends of the ironing means, of the overlapping part of the material that is being ironed and means extending substantially to the point of delivery of the material from the roller for supporting the material and for guiding the material and the overlapping ends thereof to the front of the machine.

28. In an ironing machine, a shoe, a feeding and ironing roller coacting therewith and movable toward and away from the shoe, means for supporting the roller, power operating means for the roller, driving connections between said operating means and said roller, said roller supporting means being so located and arranged with respect to the roller that the ends of the roller are free from obstruction from the supporting means and said driving connections being located opposite to the non-feeding, non-ironing portions only of the roller.

29. In an ironing machine, a roller, a heating and ironing element adapted to coact therewith, means for supporting the roller, so constructed and arranged with reference to said roller that no part of said means will be disposed in alignment with the active ironing and feeding portion of

said roller and a support extending beneath the roller and having a trough at each end thereof for supporting and guiding overlapping ends of the material around the roller and to the front of the machine. 70

30. In an ironing machine, a roller, a heating and ironing element adapted to coact therewith, means disposed in alignment with the inactive portion of the roller for supporting the roller, so constructed and arranged with reference to said roller that no part of said means will be disposed in alignment with the active ironing and feeding portion of said roller and a support extending beneath the roller and having a trough at each end thereof for supporting and guiding overlapping ends of the material around the roller and to the front of the machine. 80

31. In an ironing machine, a heating element, a roller for feeding material downwardly across said element and supporting means for said roller crossing the ends of the roller only at the upwardly traveling portion thereof and at points spaced materially beyond the ends of the roller.

32. In an ironing machine, a heating element, a roller for feeding material downwardly across said element and supporting means for said roller crossing the ends of the roller only at the inactive side thereof and at points spaced materially beyond the ends of the roller thereby leaving the ends at opposite side and top and bottom portions of the roller, free and unobstructed for the 100 passage of overlapping material.

33. In an ironing machine, a shoe, a roller for feeding the material downwardly across the shoe and means including brackets for suspending said roller, said brackets crossing the ends of the roller only at the upwardly traveling, inactive portion thereof and at points spaced materially beyond the ends of the roller.

34. In an ironing machine, a shoe, a roller for feeding the material downwardly across the shoe and means including brackets for suspending said roller, said brackets crossing the ends of the roller only at the upwardly traveling, inactive portion thereof and at points spaced materially beyond the ends of the roller, and means for receiving the material as it leaves the shoe and conducting the material and overlapping ends thereof to the front of the machine. 110

35. In an ironing machine, a heating element, a roller for feeding material downwardly across said element and supporting and driving means for said roller crossing the ends of the roller only at the upwardly traveling portion thereof and at points spaced materially beyond the ends of the roller.

36. In an ironing machine, a heating element, a roller for feeding material 130

- downwardly across said element, supporting means for said roller crossing the ends of the roller only at the upwardly traveling portion thereof and at points spaced materially beyond the ends of the roller, and means for receiving and guiding the overlapping ends of the material to the front of the machine.
37. In an ironing machine, a heating element, a roller for feeding material that is wider than the roller or the heating element into the machine and downwardly across said heating element, supporting and driving means for said roller crossing the ends of the roller only at the inactive portions thereof permitting the free passage into and delivery of the overlapping material at the ends of the roller and heating element without wrinkling or folding.
38. In an ironing machine, a heating element, a roller for feeding material across the heating element and adapted to coat therewith to iron material, said roller being movable toward and away from the heating element, power operating means for the roller and connections between said means and the roller crossing the end of the roller only at a non-feeding, non-ironing portion thereof.
39. In an ironing machine, a heating element, a roller for feeding material across the heating element and adapted to coat therewith to iron material, said roller being movable toward and away from the heating element, means operating at both ends of the roller to press the roller against the heating element, power operating means for the roller, and connections between said means and the roller crossing an end of the roller only at a non-feeding, non-ironing portion thereof.
40. In an ironing machine, a roller, a shoe, means for movably supporting said roller, means for fixedly supporting said shoe, driving connections for the roller, said supporting means for the roller, said supporting means for the shoe and driving connections being so located relative to the roller and shoe that no portions of any of said supporting means or driving connections are disposed opposite the active ironing and feeding portions of the shoe or roller.
41. In an ironing machine, a roller, a heating element adapted to coat therewith, supporting means for the roller, driving mechanism for the roller, means for supporting the material and guiding the material to said roller and heating element, and means for receiving the material from the roller and heating element and guiding the material to the front of the machine, the whole of said driving mechanism being located below the path of the material to the roller and heating element and above the path of the material from the roller and heating element.
42. An ironing machine comprising a heating element, a roller adapted to coat therewith, means operative at both ends of the roller for pressing the roller against the heating element, supporting means for the roller, supporting means for the heating element, said supporting means being so located at an end of the roller and heating element that no parts of the supporting means are disposed opposite the ironing portions of the roller and heating element, permitting one edge of the material being ironed to overlap that end of the roller and heating element and means positioned below and extending beyond that end of the roller for receiving the material from the roller and heating element and for supporting and guiding the material and the overlapping edge thereof to the front of the machine.
- In witness whereof, I have hereunto set my hand this 10th day of June, 1921.
- LEO POTTER.
